UNITED STATES PATENT OFFICE.

WILLIAM W. MANNING, OF MOUNTAINAIR, NEW MEXICO.

GLOVE-THIMBLE.

1,273,256.

Specification of Letters Patent. Patented July 23, 1918.

Application filed April 24, 1918. Serial No. 230,541.

To all whom it may concern:

Be it known that I, WILLIAM W. MANNING, a citizen of the United States, residing at Mountainair, in the county of Torrance and State of New Mexico, have invented a new and useful Glove-Thimble, of which the following is a specification.

The device forming the subject matter of this application is adapted to be applied to the ends of a finger of a glove, for the purpose of protecting the finger of the glove, the structure being of peculiar utility when employed in connection with the threshing of beans, it being a matter of common knowledge that bean threshing will wear out a pair of gloves in a short space of time, a pair of bean-thresher's gloves frequently lasting no longer than two days.

The invention aims to provide a finger-stall embodying a novel means for attaching it to a glove, the stall being so constructed that an adequate ventilation will be afforded, thereby preventing the finger of the wearer from becoming sore or overheated.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

40 In the accompanying drawings:—

Figure 1 shows in side elevation, a finger stall constructed in accordance with the invention, the same being assembled in a glove finger;

45 Fig. 2 is a longitudinal section of the stall;

Fig. 3 is an elevation showing the stall as viewed in a different position from that pictured in Fig. 1;

50 Fig. 4 is an end elevation of the stall;

And Fig. 5 is a fragmental section taken through the stall, and showing a portion of a glove finger engaged with the prong.

In carrying out the present invention 55 there is provided a cap of tubular form, the

cap being closed at its outer end as shown at 2. The cap 1 preferably is made of metal and is provided on its inner surface with spaced ventilating perforations 3. On its inner surface, the cap 1 is supplied with a single opening 4 of relatively large size, defining a cross bar 5 at the butt end of the cap 1, the opening 4 being located within the contour of the cap. The cap is provided at its sides and at the ends of the cross bar 6 with integral, unbendable, hook-shaped, glove-engaging prongs 6 extended longitudinally of the cap.

The end of the finger 7 of a glove is placed in the cap 1, portions of the finger 70 of the glove, at the sides thereof, being engaged as shown at 8, with the prongs 6, the ends 9 of the prongs being bent so that they extend into certain of the ventilating perforations 3, the construction being such that the prongs cannot be bent accidentally into an open position.

The device forming the subject matter of this application, when applied, to the fingers of a glove, will lengthen materially, 80 the life of the glove in bean threshing and similar operations wherein a glove ordinarily wears out quickly.

Having thus described the invention, what is claimed is:—

1. A finger-stall in the form of a metallic cap provided on its inner surface with spaced ventilating perforations and provided at its sides with bendable hook-shaped glove-engaging prongs having their free 90 ends extended into certain of the perforations.

2. A finger-stall in the form of a metallic cap provided on its inner surface with spaced ventilating perforations and provided on its outer surface with a single opening located within the contour of the cap and defining a cross bar at the butt end of the cap, the cap being provided at its sides and at the ends of the cross bar with bendable hook-shaped glove-engaging prongs extended longitudinally of the cap.

In testimony that I claim the foregoing as my own, I have hereto affixed my signature in the presence of two witnesses.

WILLIAM W. MANNING.

Witnesses:

SETH WILLIAMS,
C. E. BIGELOW.
